DESIGN FOR A DRESS

Helen E. Foss, New York, N. Y.

Application August 20, 1941, Serial No. 102,955

Term of patent 3½ years

To all whom it may concern:

Be it known that I, Helen E. Foss, a citizen of the United States and a resident of the city of New York, in the county of New York and State of New York, have invented a new, original, and ornamental Design for a Dress, of which the following is a specification, reference being had to the accompanying drawing forming a part hereof.

Fig. 1 is a front view of a dress showing my new design.

Fig. 2 is a rear view of the dress shown in Fig. 1.

Fig. 3 is a plan view of the jumper portion of my dress shown in Fig. 1.

I claim:

The ornamental design for a dress, substantially as shown.

HELEN E. FOSS.
